ELEVATING-TRUCK.

1,306,417.

Specification of Letters Patent. Patented June 10, 1919.

Application filed February 28, 1918. Serial No. 219,558.

To all whom it may concern:

Be it known that I, FRANK L. EIDMANN, a citizen of the United States, residing at Holyoke, county of Hampden, and State of Massachusetts, have invented certain new and useful Improvements in Elevating-Trucks, of which the following is a clear, full, and exact description.

This invention relates to elevating trucks, 10 and particularly to elevating trucks of the type in which a step-by-step jack is arranged between the elevating support and the truck base in such manner that the jack may be connected to the steering and draft handle, 15 of the truck and utilized to effect a step-by-step elevation of the platform, or other load support, upon the base through oscillation of the truck handle.

A general object of the invention is to 20 provide an improved mechanically-operated step-by-step jack for use in trucks of the aforementioned type and particularly so to incorporate this improved jack in a truck of the aforementioned type that the bulk of 25 the truck will not be in any way increased, that the jack may be operated easily in all positions of the elevating support and that it will transmit to said support substantially all of the power exerted upon the truck handle for a stroke of any length within the 30 limits of movement provided.

An important feature of the invention is the construction of the jack and its suspension in such manner that the power may be 35 transmitted to the jack endwise thereof and in the line of extension.

Another important feature of the invention is the novel jack construction in which effective gripping and retaining means are 40 arranged to operate for a stroke of any length within the range of movement of the jack operating means. Still another important feature of the invention is the novel means for releasing the elevating support 45 when it is desired to cause it to descend to its lowered position.

Other objects and important features of the invention will appear from the following description and claims when considered, in 50 connection with the accompanying drawings, in which—

Figure 1 is a plan view of an elevating truck embodying the present invention, the steering handle being shown in section;

Fig. 2 is a side elevation of the truck 55 shown in Fig. 1;

Fig. 3 is an enlarged section on the line 3—3 of Fig. 1;

Fig. 4 is a detail plan of the releasing treadle and its immediate connections; 60

Fig. 5 is a section on the line 5—5 of Fig. 4;

Fig. 6 is a horizontal longitudinal section through the jack mechanism of the truck;

Fig. 7 is a detail side elevation of the forward end of the jack; 65

Fig. 8 is a section on the line 8—8 of Fig. 6; and

Fig. 9 is a detail view showing the connections from the elevating support or platform to the jack release to prevent over-extension of the jack. 70

The illustrated truck comprises a truck base 2, having at its rear end supporting wheels 4 carried upon an axle 6, and having 75 at its forward end a steering wheel 8 mounted upon an axle 10 in a steering fork 12, having a swivel 14 received in a bearing in a bracket or gooseneck extension 16 at the front of the truck base 2. 80

The elevating support or platform 18, which, as shown, is preferably formed as an open frame with laterally extending wheel guards 20 at its rear end, is provided upon its underside with downwardly facing inclines 22 arranged to coöperate with upwardly facing inclines 24 upon the base 2, the coöoperating inclines being so arranged that when the support or platform 18 is moved toward the rear of the truck, the co- 90 operating inclines will cause the platform to be elevated while maintaining it in substantial parallelism to the base. Any other suitable means for effecting the elevation of the platform upon the base may be employed. 95

The means for effecting the rearward movement of the support or platform 18 upon the base 2 to cause the elevation of the platform upon the base, through the action of the coöoperating inclines 22 and 24, comprises a laterally rigid rectilinearly extensible mechanically-operated jack arranged lengthwise of the truck and having its relatively extensible parts pivotally connected respectively to the base and to the platform, 105 the jack being wholly supported by its pivotal connections, somewhat after the manner of the jack described and claimed in

United States Letters Patent #1,201,180 granted October 10, 1916. The illustrated jack comprises a supporting frame made up of lateral straps 26, having at their forward 5 ends trunnions 28 received in bearings 30 in the base portion 32 of the bracket or cross-piece 16. At their other ends the straps 26 are connected to the cylindrical outer casing 34 of the retaining means of the jack, the 10 rod 36 of the jack sliding axially through this casing, and being pivotally connected at 38 to ears on the underside of the support or platform 18.

The trunnions 28 have elongated base portions 40 received in slots 42 of a cylindrical slide 44, carrying the lifting or post advancing means of the jack. This lifting means comprises gripping members 46 having conical outer surfaces and shaped upon their inner surfaces to fit the rod 36, these members being received in a corresponding conically-shaped opening in the slide 44, whereby when they are moved toward the small end of said opening they tend to wedge against 20 the rod 36 and grip the rod, this wedging movement being in a direction to cause the rod to travel with the slide 44 when the slide is moved toward the right in each of the figures in the drawings. A spring 48 bearing 30 at one end against a washer 50, abutting against the ends of the gripping members 46 and at its other end against a yoke 52 spanning the open end of the slide 44, tends to force the members 46 into gripping engagement 35 with the rod 36.

The retaining means for holding the jack in extended position comprises gripping members 54 shaped like the gripping members 46 and received in a correspondingly 40 shaped recess in the cylindrical casing 34, the members 54 being normally forced into gripping engagement with the rod 36 by a spring 56 bearing at one end against a washer 58 and at its other end against a retaining yoke 60 spanning the open end of 45 the casing 34.

It will be seen that movement of the rod to the right tends to move the gripping members 54 toward the larger end of the 50 recess in which they are located, and thus to release them from gripping engagement with the rod, but that any tendency of the rod to move toward the left will be resisted because of the movement of the members 54 55 toward the smaller end of the recess in which they are located.

In order to effect the reciprocation of the slide 44 and thus effect the extension of the jack, means is provided for connecting this 60 slide to the steering handle 62 of the truck. The steering handle 62 is provided with a fork 64 at its lower end, which embraces and is pivotally connected at 65 with an extension 66 of the swivel 14 above its bearing in 65 the bracket 16. The steering handle can

thus swing in a vertical plane upon the swivel 14, and when swung about the axis of the swivel serves to turn the swivel and with it the steering wheel 8.

The connections between the steering handle 62 and the slide 44 comprise a multiplying lever 68 fulcrumed upon a horizontal shaft 70 in the bracket 16, the lever 68 having a long arm above the shaft 70 and a short arm depending below the shaft 70, the 75 short arm being connected by a link 72 to a cap 74 threaded upon the forward end of the slide 66, the link 72 being received between the ears 76 upon said cap. At its upper end the lever 68 is provided with a link 80 78 by which it may be connected to the steering handle 62 when said handle is in substantially upright position, the link 78 being forked at its forward end so that it may embrace the steering handle 62, and each of 85 the forked members being provided with a notch 80 adapted to receive a pin or lug 82 upon the side of the handle 62 when the handle is in such position that its pivot 65 is substantially parallel to the shaft 70. To 90 facilitate the connection of the handle 62 with the jack, when it is desired to operate the jack, each of the forked members of the link 78 has an inclined forward end 84 adapted to ride upon the pin 82 when the 95 link 78 is resting upon the supporting lug 86 on the lever 68, and the pins 82 are moved into engagement with the forward ends 84 of the forked members of the links 78. A second lug 88, upon the lever 68, is adapted 100 to engage a stop 90 on the bracket 16 and limit the rearward movement of the long arm of the lever 68 about its fulcrum 70.

It will be noted that the pins 82 are located comparatively near the pivot 65 of the 105 steering handle 62, thus making the steering handle a multiplying lever of the second class, and that the power thus multiplied by the steering handle is transmitted to the slide 44 through a second multiplying lever 110 of the first class, namely, the lever 68 having a long upper arm and a short lower arm. It will further be noted that this multiplying lever system is so arranged that it does not increase materially any dimension of the 115 truck and that it does not interfere in any way with the arrangement and movement of the elevating support or platform 18 upon the truck base, or with the manipulation of the truck when the steering handle is disconnected from the elevating mechanism to steer the truck.

The mechanism for releasing the jack to permit the support or platform 18 to return to its lowered position when it has been elevated will now be described: Carried upon the side straps 26 of the jack frame are two pins or studs 92, projecting into a slot 94 in the slide 44 and so located in the path of movement of the gripping members 46 of the 130

lifting clutch, or rather in the path of movement of washers 96 bearing against the ends of these gripping members that when the slide 44 is moved into its retracted position,

5 the studs 92 will engage the washers 96 and push the members 46 out of gripping or clutching relation to the rod 36.

In order to release the retaining means, treadle-controlled means is provided for 10 pushing the gripping members 54 out of clutching relation to the shaft 36. The illustrated means comprises pins or studs 98 carried upon arms 100 rising from the ends of a rock-shaft 102 having its bearings 15 in depending ears upon the straps 26. These studs 98 project through slots in the straps 26 and when the rock shaft 102 is rocked to move these studs toward the right in a manner hereinafter to be described, the 20 studs are adapted to engage a washer 104 bearing against a sleeve 106 surrounding the rod 36 and arranged to slide through the casing 34, this sleeve at its other end bearing against the second washer 108, which 25 abuts against the smaller ends of the gripping members 54.

One of the studs 98 is extended through its arm 100 and receives upon this extension a link 110 connected to an arm 111 upon a 30 second rock shaft 112 adapted to be rocked through connections to a treadle 114. The treadle 114 is mounted upon one arm of the bell-crank lever, fulcrumed at 116 on the bracket 16, and the other arm of this bell-crank is connected by a link 118 to a second arm 120 on the rock shaft 112. A spring 122 bearing against a pin upon the link 118 at one end and against a washer 124 abutting against ears on the cross-piece 32 maintains 35 said treadle in its uppermost position. Depression of the treadle by the foot of the operator moves the studs 98 to disengage the retaining means in the manner hereinabove described.

40 In order to prevent over-extension of the jack, which might carry the inclines 22 beyond the inclines 24, means is provided for automatically releasing the retaining means when the lifting or rod advancing means

45 tends to carry the support or platform 18 beyond the desired elevated position. The illustrated means comprises a link 126 connected at one end to the extension of the stud 98, to which the link 110 is connected.

50 This link passes through an eye 128 depending from the underside of the support or platform 18, and is threaded beyond said eye to receive a pair of nuts 130 forming an adjustable stop. As shown in Fig. 9 of the drawings, when the platform is in its lowered position the stop 130 is spaced from the eye 128, but as the platform is moved toward the right to effect its elevation, the eye 128 slides over the link or rod 126 until it

55 engages the stop 130 when further move-

ment of the platform toward the right will cause the rocking of the shaft 102 and the disengagement of the retaining clutch members 54.

What I claim as new is—

1. In an elevating truck, the combination with the truck base, an elevating support and a jack connected to said base and to said support for effecting the elevation of said support, said jack comprising step-by-step lifting means and retaining means, of connections between said support and said retaining means operating to release said means when said jack tends to move said support beyond a predetermined point. 70

2. In apparatus of the class described, the combination with a wheeled truck base and an elevating support arranged for combined longitudinal and up and down movements of approach and separation in substantial parallelism, and rectilinearly separable jack members respectively pivotally connected to said aforementioned separable parts, whereby said jack may swing bodily during the movements of approach and separation of said parts, of moving and retaining means associated with the separable jack members, and means mounted upon one of the first mentioned members and having operative connection with said retaining means in any swinging position of said jack for releasing said retaining means. 85

3. In an elevating truck, the combination of a base and an elevating platform, of means for elevating said platform comprising a jack having telescoping members pivotally connected respectively to said base and to said platform and arranged to swing bodily during the elevating operation, means for effecting the extension of said jack comprising a carrier arranged to reciprocate upon one of said telescoping members and carrying means for gripping the other member during its movement in one direction, means for retaining said jack in 100 extended position, and means mounted upon said base and operable in any angular position of said jack for releasing said retaining means. 105

4. In an elevating truck, the combination with a truck base and an elevating support, of telescoping jack members extending lengthwise of the truck and pivotally connected respectively to said base and to said support, and mechanical means for effecting the extension of said jack to elevate said support on said base, comprising lifting means arranged to reciprocate on one jack member and to engage and move the other relatively thereto, and retaining means also 120 carried by the first mentioned jack member, both of said means being located between said pivotal connections. 125

5. In an elevating truck, the combination with a truck base and an elevating support, 130

of telescoping jack members extending lengthwise of the truck, pivotally connected respectively to the base and to the support and arranged to telescope between said pivotal connections, and means for effecting the extension of said jack, comprising a reciprocating lifting clutch having the limits of its reciprocating movement between said pivotal connections, and a retaining clutch also operating between said pivotal connections.

6. In an elevating truck, the combination with a truck base and an elevating support, of rectilinearly relatively movable jack members, pivotally connected respectively to said base and to said support, said jack extending lengthwise of said truck and telescoping between said pivotal connections, a jack extending clutch reciprocating on one member between said pivotal connections and arranged to engage and move the other member, clutch reciprocating means extending across one of said pivots, and a truck handle arranged to be connected to said last mentioned means.

25 7. In an elevating truck, the combination with the truck base and an elevating support, of telescoping jack members pivotally connected respectively to said base and to said support, said jack being arranged lengthwise of said truck and have its pivotal connection to the base at the forward end thereof, a jack extending clutch and a retaining clutch located between said pivotal connections, and a reciprocating carrier for said extending clutch arranged to operate in the line of extension of said jack and projecting beyond the forward end of said jack.

8. In an elevating truck, the combination with the truck base and an elevating support, of telescoping jack members pivotally connected respectively to said base and to said support, said jack being arranged lengthwise of said truck and having its pivotal connection to the base at the forward end thereof, a jack extending clutch and a retaining clutch located between said pivotal connections, and a reciprocating carrier for said extending clutch arranged to operate in the line of extension of said jack and projecting beyond the forward end of said jack, a truck steering handle and means for operatively connecting said handle to said clutch reciprocating means.

55 9. In an elevating truck, the combination with the truck base and an elevating support, of a jack pivotally connected at its respective ends to said base and to said support, said jack extending lengthwise of said truck and comprising a jack post connected to the platform, and a jack base provided with trunnions having bearings on said

truck base, a post retaining clutch carried by said jack base, a post advancing clutch and a carrier therefor arranged to reciprocate between said trunnions in the line of extension of said jack.

10. An elevating truck having, in combination, a wheeled base, a steering and draft handle associated with one of the wheels of said base, an elevating support and means for elevating said support, including a jack arranged lengthwise of the truck, said jack comprising a jack post having a pivotal connection with said support and a jack base, into which said post telescopes, having a pivotal connection with the truck base, a post retaining clutch and a post advancing clutch operating upon said post between said pivotal connections, means extending across one of said pivots and reciprocating in the line of extension of the jack for operating said post advancing clutch, means normally tending to engage said clutches and means carried by said base for simultaneously releasing said clutches.

11. In an elevating truck, the combination with a wheeled truck base and an elevating support, of a mechanically-operated jack arranged lengthwise of said truck and having pivotal supporting connections respectively to said base and to said support, said jack comprising a telescoping base and post, a retaining clutch carried by said base, a post advancing clutch and a carrier therefor guided in and reciprocating lengthwise of said jack base in the line of extension of said jack, a steering and draft handle for the truck and connections between said handle and said clutch carrier, comprising a link pivotally connected to said carrier in proximity to one of the jack supporting pivots.

12. In an elevating truck, an elevating jack adapted to be arranged lengthwise of said truck, said jack comprising a telescoping base and post, trunnions on said base adapted to support said jack for bodily swinging movement, a post retaining clutch mounted on said base, a post advancing clutch and a carrier therefor guided by and reciprocating centrally of said base and coaxially with said post, and operating connections to said carrier in proximity to said trunnion axis, whereby said connections are not materially disturbed by the swinging movement of said jack.

Signed at Holyoke, Massachusetts, this 15th day of February, 1918.

FRANK L. EIDMANN.
